UNITED STATES PATENT OFFICE.

AMUND U. JAASTAD, OF BOSTON, MASSACHUSETTS.

SUPERHEATER.

SPECIFICATION forming part of Letters Patent No. 642,231, dated January 30, 1900.

Application filed September 25, 1899. Serial No. 731,552. (No model.)

To all whom it may concern:

Be it known that I, AMUND U. JAASTAD, of Boston, county of Suffolk, and State of Massachusetts, have invented an Improvement in 5 Superheaters, of which the following description, in connection with the accompanying drawings, is a specification, like letters on the drawings representing like parts.

The present invention relates to a super- 10 heater for boilers, one object of the invention being to so construct the superheater that it can be easily attached to existing boilers without modifying the construction thereof and without interfering with the ordinary use of 15 the boiler if the superheater is out of order and requires repairs.

A further feature of the invention consists 20 in so arranging the superheater that it is readily accessible for repairs even when the boiler is in operation and also so that it is not acted 25 upon by the gases until they have reached a point where they are about to leave the boiler and have given up the greater part of their heat in converting the water into steam.

25 The invention is herein shown as applied to a Babcock & Wilcox water-tube boiler, although it may obviously be applied to boilers of other types.

In accordance with the invention the super- 30 heater comprises a continuous series of tubes arranged in any suitable or usual way and contained in the chamber below the steam-drums, said tubes occupying that part of the chamber which is between the boiler-tubes 35 and the draft-outlet, so as not to be acted upon by the gases until after they have left the last pass in the boiler.

The superheater is shown as having two 40 sections, each of which is provided with a pair of headers, one of which forms the inlet and the other the outlet, and the inlet-headers are arranged to be directly coupled to the cross connection which connects together the several steam-drums when, as is usually the 45 case, there are two or more of such drums all connected with the same system of water-tubes. The said cross connection for the steam-drums is usually provided with an inlet from each drum and a common outlet, 50 from which the steam is taken to the place where it is to be used, and the superheater embodying the present invention is arranged

to have its inlet and outlet passages connected with the said steam-outlet, with valves interposed, so that the steam can be caused to 55 pass through the superheater or be taken directly from the boiler or partly from each; as may be desired. It is only necessary, therefore, to connect with the ordinary steam-outlet of a boiler a coupling containing a valve 60 and a branch connection beyond the said valve, having two inlets and a single outlet, one of the said inlets being connected with the superheater and the other with the coupling aforesaid, which is connected with the 65 main outlet-passage from the boiler. The superheater itself is provided with valves at both its inlet and its outlet end, the latter valve being interposed between the said branch passage and the tubes of the super- 70 heater, so that by closing the said valves the superheater can be completely cut off and the steam allowed to pass directly from the boiler by opening the boiler-valve.

Water-tube boilers of the Babcock & Wilcox make or similar type as commonly constructed are provided with a series of baffles whereby the products of combustion are caused to pass upward across the tubes and thence downward and again upward, the 80 spaces between the said baffles being usually designated as the first, second, and third "passes," there being commonly two baffles and three passes.

The superheater-tubes in accordance with 85 the present invention are located in or beyond the third pass, (or, if there are more than three passes, in or beyond the last pass,) so as not to be acted upon by the gases until the heat has been largely extracted therefrom 90 and used in converting the water into steam. As herein shown, provision is made for flooding the superheater, or, in other words, filling the superheater-tubes with water when the boiler is first started, (to be afterward drawn off;) but such flooding is not essential with 95 this construction, since the heat will be so greatly reduced before reaching the superheater-tubes that there is practically no danger of burning out the superheater.

100 Figure 1 is an elevation, partly in section, of a superheater embodying the invention shown as applied to a Babcock & Wilcox boiler, the section being mainly taken on the

line x' of Fig. 2. Fig. 2 is a transverse section of the same, taken on the line x^2 of Fig. 1, the outlet connections being omitted from Fig. 2. Fig. 3 is a partial top plan view of the boiler, showing the end where the superheater is placed. Figs. 4 and 5 are details to be hereinafter referred to; Fig. 6, a vertical section showing a modification in which the superheater is applied to a boiler having only two water-drums; Fig. 7, a partial top plan view of the same; and Figs. 8, 9, and 10, sectional views showing further modifications, Fig. 8 being a section on the line x^8 of Fig. 9, Fig. 9 a horizontal section on the line x^9 of Fig. 8, and Fig. 10 a vertical section on the line x^{10} of Fig. 8.

As shown in Fig. 1, the water-drums A, which in this type of boiler also constitute the steam-chambers, are each provided with an outlet-passage A^2 , which connects with a single outlet A^3 through a cross connection A^4 . This is the common construction in boilers of this type, and the connection is made in substantially the same way to a common steam-outlet without regard to the number of water-drums which are used.

In accordance with the present invention the superheater is so arranged that its inlet portion can be readily connected to one or both ends of said cross connection, while its outlet portion is connected to one branch of a double inlet coupling-piece, the other branch of which is arranged to be connected directly with the boiler-outlet, the said coupling, however, being provided with a valve in each branch.

The superheater is preferably made in two parts, each of which is the duplicate of the other, the inlet of one part being coupled to one end of the cross connection A^4 , and the inlet of the other part being coupled to the opposite end of said cross connection, while the outlets of said parts are both connected with the coupling aforesaid, the object of this arrangement being mainly to obtain a more symmetrical arrangement and greater heating-surface for the superheating-tubes.

Referring to Figs. 1 and 2, the superheater embodying the invention comprises an inlet tube a , provided with a valve b , arranged to be coupled directly to the end of the cross connection A^4 , so that when the valve b is open the steam will pass from the boiler into the said inlet-tube a , which terminates in the header a^2 , and thence through a series of tubes a^3 to an outlet-header a^4 , which is coupled in any suitable or usual way with the main steam-outlet from the boiler.

As herein shown, the parts above described are duplicated, there being an inlet-tube connected with each end of the cross connection A^4 , the several tubes a^3 overlapping and being staggered, as shown, while the outlet-tubes a^4 are connected with a cross-tube a^5 , which is arranged to be connected with the main steam-outlet through the coupling-piece c , which is provided with two inlets and a

single outlet c^2 . The said coupling itself is arranged to have one of its branches connected with the main boiler-outlet A^3 , as best shown in Fig. 1, and the boiler-outlet and the superheater-outlet are respectively controlled by means of suitable valves d and e , it being obvious that when the valve d is closed the steam from the boiler cannot pass directly to the outlet c^2 , but must pass into the inlet-pipes a , and thence through the superheater, which thus practically constitutes a by-pass. If, on the contrary, the valve d is open and the valve e closed, the steam will pass directly from the boiler to the outlet, and in order to cut off the superheater entirely from the boiler it is necessary only to close the valves b , so that no steam can pass into the superheater at either end thereof. Assuming, therefore, that the superheater is in use, the steam will pass from the tube a^4 through the valves b into the tubes a , and thence across the chamber below the steam-drum, and upward to the cross-tube a^5 through the valve e to the outlet c^2 . If, however, anything happens to the superheater so that it requires repairs or if its use would be otherwise detrimental or undesirable, it is necessary only to shut the valves b and the valve e and open the valve d , in which case the steam will pass directly from the boiler to the outlet, so that there is no necessity for shutting down the plant pending repairs. Furthermore, it may in some cases be desirable to use both saturated and superheated steam, and it is obvious that the valve d affords means for permitting any desired amount of steam direct from the boiler to mix with the superheated steam. To facilitate regulation, the valve d is shown as having a small by-pass d^2 , provided with a valve d^3 , so that the regulation can be easily and accurately accomplished.

As best shown in Fig. 1, the superheater is contained in that portion of the chamber below the steam-drum which is in or beyond the third pass, the said chamber being divided by baffles B into three passes, so that the gases or products of combustion do not reach the superheater until they have passed wholly beyond the boiler-tubes C . Furthermore, while it is obvious that the inlet and outlet tubes of the superheater are not essentially duplicated, as shown, it is desirable that they should be so duplicated in order that the tubes may be more readily removable when repairs are necessary. As best shown in Fig. 2, the said tubes, which extend transversely across the chamber below the steam-drum, can be reached through openings provided with covers D , and by having the tubes overlapping and staggered, as shown, a large amount of heating-surface is obtained, while the tubes at the right-hand end can be easily taken out through the left-hand door even if a number of boilers are arranged close together, as is usually the case.

The inlet-header a^2 may be provided, as shown, with an inlet-pipe f , communicating

with the pipe g , connected with the water-drums or other source of water-supply and controlled by a valve g^2 , so that the superheater-tubes may be flooded, if desired, when the boiler is started up, the said tube g being provided with another valve g^3 for drawing off the water after steam is actually generated. The flooding in this case, however, is not essential, but is only provided for as a safeguard, since the heat of the gases will be so far reduced by the time they reach the superheating-tubes that there will be no danger of burning out the superheater.

From the foregoing description it will be seen that a superheater embodying the present invention can be easily applied to boilers of existing types without modification in the boiler itself or its connections. The valves b , d , and e and the coupling c form a part of the superheater and may be readily connected to the cross connection and the main steam-outlet of the boiler, respectively, while after the superheater is connected the boiler may be used with or without the superheater, as may be desirable or necessary.

It is obviously not essential that the superheater should be arranged as shown in Figs. 1, 2, and 3, since it may be desirable in some cases to provide for a larger heating-surface in the same space or to arrange the superheater for use with a boiler having a different number of water-tubes. Fig. 5 shows in detail a pair of headers in which a number of small tubes are arranged in two rows along each header instead of a single row, as shown in Fig. 4.

As shown in Figs. 6 and 7, for example, the superheater is applied to a boiler having only two drums, the only difference in this case being that the outlet-headers are adjacent to each other and terminate in a common coupling-piece a^30 instead of cross-tube a^3 , the said coupling-piece being arranged to be connected with one branch of the coupling c .

In Figs. 8, 9, and 10 the headers are arranged substantially as shown in Figs. 6 and 7; but the tubes a^3 are curved in order to obtain a greater heating-surface, the outlet-headers being adjacent to each other and communicating with a coupling a^30 , as before.

It is not intended to limit the invention to the specific construction herein shown and described, since modifications may obviously be made without departing from the invention.

I claim—

1. A superheater for boilers comprising a system of tubes located in the boiler; inlet and outlet tubes connected with the said tube system and extending therefrom to a point outside the boiler; couplings for said tubes whereby they are adapted to be connected to the steam-passage at a point outside the steam-drum; and valves respectively controlling the said superheater and the said steam-passage, substantially as described.

2. The herein-described superheater which

comprises a set of tubes extending transversely across the boiler and located above the boiler-tubes and beyond the last baffle-plate; and inlet and outlet passages connected with said tubes and adapted to be connected with the steam-outlet from the boiler at a point outside the steam-drum, as set forth.

3. A superheater comprising an inlet-passage provided with a valve adapted to be coupled directly with the steam-outlet from the boiler at a point outside of the steam-drum; a series of superheating-tubes leading from the said inlet-passage through the boiler; an outlet-passage connected with the steam-outlet at a point outside of the steam-drum; and a valve in the steam-outlet interposed between the inlet and outlet passages of the superheater, as set forth.

4. A superheater comprising an inlet-duct adapted to be connected with the end of the cross connection which connects the water-drums of the boiler with the main steam-outlet; steam-passages extending from said inlet-duct transversely across the heat-chamber in the boiler; an outlet-duct extending from the opposite ends of said steam-passages to a coupling connected with the boiler-outlet, said coupling having two branches each provided with a valve, one connected directly with said boiler-outlet and the other with the superheater-outlet; and valves controlling the superheater-inlets, substantially as described.

5. A superheater having its inlet and outlet ducts coupled with the boiler-outlet at a point outside of the steam-drum, and a main valve in said boiler-outlet between said ducts, whereby a direct outlet may be afforded from the boiler, as set forth.

6. A superheater having its inlet-ducts coupled to the cross connection outside of the steam-drum and its outlet-ducts coupled to the main steam-outlet beyond said cross connection; a main valve in said main steam-outlet between said ducts; and a by-pass valve controlling a by-pass around said main valve whereby saturated and superheated steam may be used at the same time and the proportions regulated, substantially as described.

7. A superheater comprising substantially vertical headers connected together by substantially horizontal tubes, said tubes extending transversely through the boiler above the water-tubes and below the drum; inlets coupled to the ends of the drum cross connection and extending to the outer headers of the superheater; outlets from the inner headers of the superheater extending between the steam-drums to one of the inlets of a branch connection having two inlets and one outlet, the other inlet thereof being connected to the main steam-outlet from the steam-drums; and a valve in said main steam-outlet, substantially as described.

8. A superheater having inlets a and out-

lets a^4 ; couplings for said inlets provided with valves b at the ends of the cross connection A^4 ; a branch connection c having one of its inlets communicating with the superheater-outlet a^4 and its other inlet communicating with the steam-outlet A^3 ; and the valves d and e controlling the inlets of said branch connection, as set forth.

In testimony whereof I have signed my name to this specification in the presence of 10 two subscribing witnesses.

AMUND U. JAASTAD.
